DESIGN FOR A PIPE BIT

Chester C. Doty, Silver Creek, N. Y.

Application August 19, 1941, Serial No. 102,950

Term of patent 14 years

To all whom it may concern:

Be it known that I, Chester C. Doty, a citizen of the United States, residing at Silver Creek, in the county of Chautauqua and State of New York, have invented a new, original, and ornamental Design for a Pipe Bit, of which the following is a specification, reference being had to the accompanying drawing, forming part thereof.

embodying my new design, the bottom plan being similar.

Figure 2 is a view in side elevation of the bit, the opposite side being similar, and

I claim:

The ornamental design for a pipe bit, substantially as shown and described.

CHESTER C. DOTY.
